UNITED STATES PATENT OFFICE.

HARMON GIEBEL, OF NEW YORK, N. Y.

DESIGN FOR DECORATIVE FABRIC.

SPECIFICATION forming part of Design No. 32,267, dated February 20, 1900.

Application filed January 13, 1900. Serial No. 1,388. Term of patent 7 years.

To all whom it may concern:

Be it known that I, HARMON GIEBEL, a citizen of the United States, residing in the city of New York, borough of Brooklyn, county of Kings, and State of New York, have invented and produced a new and original Design for Decorative Fabrics, of which the following is a specification, reference being had to the accompanying drawing, forming a part thereof.

In the accompanying drawing the figure represents a front view of my new design, which consists, essentially, of an elongated horizontal panel A, having near either extremity the representation of a shield *s s*, surmounted by an eagle *e e*, each shield being flanked on either side with looped flags or standards *ff*,

together with a central vertical panel *c*, flanked on both sides with the representation of larger flags *F F*, looped in a quarter-circle, the inner edge or back of each flag extending ²⁰ along a vertical side of the central vertical panel *c*.

Having described my invention, what I claim as new, and desire to secure by Letters Patent, is—

The design for a decorative fabric, as herein shown and described.

HARMON GIEBEL.
